Attorney

UNITED STATES PATENT OFFICE.

MORRY L. COGSHALL, OF DALHART, TEXAS.

TOY BLOCK.

Application filed February 21, 1924. Serial No. 694,304.

To all whom it may concern:

Be it known that I, MORRY L. COGSHALL, a citizen of the United States, residing at Dalhart, in the county of Dallam and State 5 of Texas, have invented certain new and useful Improvements in Toy Blocks, of which the following is a specification.

This invention relates to toy blocks particularly intended for use of children for 10 amusement and educational purposes.

An important object of the invention is to provide a toy block which is provided with attaching means and may be employed by children for constructing various structures.

15 A further object of the invention is to provide building blocks of this character which may be secured together to form various word combinations.

20 A further object of the invention is to provide a device of this character which will furnish a pleasing pastime for children and likewise instructive.

25 Other objects and advantages of this invention will be apparent during the course of the following description.

In the accompanying drawings forming a part of this specification and in which like numerals are employed to designate like parts throughout the same:

30 Figure 1 is a top plan view showing a plurality of the blocks secured together,

Figure 2 is a perspective view of one form of the device, and

35 Figure 3 is a perspective view of another form of the device.

In the drawings, wherein for the purpose of illustration is shown the preferred embodiment of my invention, the numeral 5 generally denotes a block which may be constructed of wood or any desired material and may be square, rectangular or any desired shape. On the upper face of the block I provide letters 6 which may be of any size, color or shape desirable and the number of letters comprising the set would depend on the number of blocks thereof, preferably comprising the entire alphabet.

40 For the purpose of rigidly securing the blocks together in numerous formations a

cylindrical extension bar 7 is formed on the 50 sides of the blocks, the said bar 7 being adapted to engage suitable grooves 8 formed in the sides of the blocks thereby securing the blocks rigidly together.

In use, the blocks may be connected as 55 shown in Figure 1 and constructed to form numerous word combinations. It is to be noted that a plurality of extension bars 7 may be formed on different sides of the blocks and also numerous grooves adapted to 60 receive the bars, thus enabling the blocks to be secured to one another in numerous positions and readily permitting the user to construct numerous structures such as pyramids or the like.

65 It is to be understood that the form of my invention herewith shown and described is to be taken as the preferred example of the same, and that various changes as to the shape, size and arrangement of parts may 70 be resorted to without departing from the spirit of the invention, or the scope of the subjoined claims.

Having thus described my invention, I 75 claim:

1. Toy blocks of the character described, comprising flat sided bodies each having a vertical groove formed in the side extending from the top or bottom flat side thereof to a point approximately midway of the body, 80 and an extension bar formed on another side of the body for engaging in a groove of another block.

2. Toy blocks of the character described, comprising flat sided bodies each having a 85 vertical groove formed in the side extending from the top or bottom flat side thereof to a point approximately midway of the body, and an extension bar formed on another side of the body and extending from the top or 90 bottom of the body opposite from which said groove extends, said bar adapted to engage in the groove of another block.

3. Toy blocks of the character described, comprising a plurality of flat sided bodies 95 each having a vertical groove formed in the side extending from the top or bottom thereof to a point approximately midway of the

body forming an abutment at said midway point, and an extension bar formed on another side of said body extending from the top or bottom opposite to that from which said groove extends and terminating at a point midway of the block, said bar adapted to engage in the recess of another block with the end thereof which terminates midway of

the block contacting with the abutment formed at one end of the groove.

In testimony whereof, I have affixed my 10
signature in the presence of two witnesses.

MORRY L. COGSHALL.

Witnesses:

THOMAS F. GOODRICH,
DEAN KIBLY.
